UNITED STATES PATENT OFFICE.

GEORGE W. NICOLAUS, OF BALTIMORE, MARYLAND, ASSIGNOR OF THREE-FOURTHS
TO WILLIAM R. HOWARD, JOHN W. DEBELIUS, AND SAMUEL W. LIPPINCOTT, ALL
OF BALTIMORE, MARYLAND.

SKID.

1,158,829.

Specification of Letters Patent.

Patented Nov. 2, 1915.

Application filed August 20, 1914. Serial No. 857,791.

To all whom it may concern:

Be it known that I, GEORGE W. NICOLAUS, of Baltimore city, in the State of Maryland, have invented certain new and useful Improvements in Skids; and I do hereby declare the following to be a full, clear, and exact description of the invention, such as will enable others skilled in the art to which it appertains to make and use the same.

10 The object of this invention is to provide simple and highly efficient means for raising and lowering heavy packages to and from wagons, and is especially adapted for handling large rolls of print paper, boilers, 15 casks and the like.

In the accompanying drawings, Figure 1 is a side elevation. Fig. 2 is a plan view. Fig. 3 is a bottom plan view with the chains omitted. Fig. 4 is a side view of a portion 20 of a wagon-body showing a load on the skid. Fig. 5 is an end view of a wagon-body showing the skid tilted, in full lines, with the load in position to be placed on the skid or as discharged therefrom, the position of the 25 loaded skid on the wagon being indicated in dotted lines. Fig. 6 is an enlarged view of the means for securing the chains to one side of the wagon-body. Fig. 7 is a fragmentary view showing the plate upon which 30 the skid rests.

Referring to the drawings, 1 designates the body of the skid which is preferably composed of two U-shaped parallel beams suitably braced together and in which are journaled the axle rods 2 of rollers 3, the latter projecting a short distance beneath the plane of the side bars. At one end the skid has a handle bar 4 extending laterally thereof, and at its other end a nose plate 5 which intersects the plane of the top of the skid. This 40 top I have shown in the form of a concaved rest 5' secured to the upper flanges of the side bars and extending the full length of the latter, the curvature of the top serving to insure the proper seating of a cylindrically-shaped bundle or package, as shown in Fig. 4. The nose 5 is especially adapted for use in loading, as shown in Fig. 5.

The length of the skid may be varied, but 50 for ordinary uses I have found it advantageous to have its length slightly in excess of the width of the wagon body in connection with which it is to be used. For the purpose of detachably connecting the skid to the wagon-body to aid in loading and un-

loading, I employ flexible connections between the skid and the wagon, such connections being readily detachable. According to means shown two chains 6 are secured each at one end to one of the side-bars of 60 the skid at a point between the transverse center and what might be termed the near or inner end of the skid. At their free ends these chains 6 have hooks 7 connected thereto by means of turn-buckles 8, said hooks being so formed as to engage the far or outer longitudinal edge of the wagon-body 9 as shown in Figs. 5 and 6. These chains are of greater length than the width of the wagon so that when the skid occupies an 65 inclined position, as shown in Fig. 5, the ends of the chains will extend diagonally beneath the plane of the wagon-body and thus afford, by reason of their bearing on the wagon-body, additional support to the 70 skid, which latter is designed to fulcrum on the inner longitudinal edge of the wagon.

The greater part of the length of the skid being above the wagon body, the skid with its load may readily be turned into position 80 on the wagon body, fulcruming on the edge of the wagon. When in its inclined position the skid is supported not only by bearing against the wagon body, but it is also supported at points beneath such bearing by 85 the portion of the chains extending beyond the edge of the wagon.

For the purpose of insuring the easy sliding of the skid transversely of the wagon I provide a bearing plate 10 the length of 90 which corresponds to the width of the wagon. At one end this bearing plate has a downwardly turned flange 12 for engaging the outer longitudinal edge of the wagon-body and thereby prevent the plate 95 from moving when the skid is being slid off the wagon.

For the purpose of preventing injury to the sidewalk or curb by the lower end of the skid I may employ a wear plate 13, as shown in Fig. 5, said plate having a flange 14 for extending over the edge of the curb. To aid in loading heavy articles on the skid while the latter is in a horizontal position on the wagon, I may employ inclined blocks 15, as 100 shown in Fig. 4, but any suitable means may be used for this purpose.

In practice, when it is desired to load heavy articles on a wagon, the skid is made to occupy an outwardly inclined position as 110

shown in full lines Fig. 5, the lower end of the skid resting on the wear plate 13, while the side bars bear against the inner longitudinal edge of the wagon body. The load 5 is brought over nose 5 of the skid, and after being tilted into engagement with the concaved top, the skid is turned into a horizontal position, and is then moved transversely of the wagon so as to project substantially 10 equal distances on both sides of the latter. When a series of articles are to be loaded each may be successively rolled from the skid over the inclines 15. In unloading, each article is successively brought on to the 15 top of the skid, and the latter is then moved transversely of the wagon and then allowed to tilt, the weight of the skid and load being largely taken up by the chains by which the skid is connected to the outer longitudinal 20 edge of the wagon-body.

I claim as my invention:

1. A skid comprising an elongated body 25 designed to extend transversely of a wagon body and to occupy an inclined position relatively thereto when loading and unloading with the major portion of the skid above the plane of the wagon body when in such inclined position, chains attached to opposite sides of said body at points between the

lower end thereof and the point of contact 30 of the skid with the wagon body when in its inclined position, and means carried by said chains for attaching the free-ends thereof to the wagon body.

2. A skid comprising an elongated body 35 designed to extend transversely of a wagon body and to occupy an inclined position relatively thereto in loading and unloading, with the major portion of the skid above the 40 plane of the wagon body when in such inclined position, chains attached to opposite sides of said body near what is its lower end when in an inclined position, and means carried by said chains for detachably connecting the free ends thereof to the side of the 45 wagon body opposite to that against which the skid is designed to rest, said chains being of such length that the ends thereof connected to the skid will extend below the plane of the wagon body when the skid occupies its inclined position.

In testimony whereof, I have signed this specification in the presence of two subscribing witnesses.

GEORGE W. NICOLAUS.
